UNITED STATES PATENT OFFICE.

ROBERT A. FONTAINE, OF ROANOKE, VIRGINIA, ASSIGNOR OF ONE-HALF TO G. T. GREER,
OF ROANOKE, VIRGINIA.

BRICK-HANDLING APPARATUS.

1,252,896.

Specification of Letters Patent.

Patented Jan. 8, 1918.

Application filed February 5, 1917. Serial No. 146,754.

To all whom it may concern:

Be it known that I, ROBERT A. FONTAINE, a citizen of the United States, residing at Roanoke, in the county of Roanoke and State of Virginia, have invented a new and useful Brick-Handling Apparatus, of which the following is a specification.

This invention relates to apparatus for handling bricks, one of its objects being to provide means whereby a hack of brick can be elevated bodily onto a special form of truck provided therefor and conveyed to a point of delivery where it can be lowered bodily to the ground and left stacked, the handling means being removable readily from the hack so that it can be removed to the loading point where another hack can be taken and conveyed to the point of discharge.

20 A further object is to provide a special form of truck which can be readily actuated for the purpose of loading a hack thereon or unloading it therefrom and which is used in connection with a brick gripping structure of novel form constituting the body of the truck while the bricks are being conveyed.

30 A further object is to provide brick handling apparatus in which the bricks can be stacked and which apparatus, as soon as it is lifted, will operate to clamp upon the bricks so as to hold them against displacement relative to each other, thus causing them to maintain their proper positions in the body until said body has been lifted onto the truck, the lowering of the body to the ground also resulting in a gripping of the bricks so that they will not fall therefrom.

40 It is a well known fact that where the usual methods are used for handling bricks in conveying them from the kilns to the yard or from the kilns or yard to the point of use, considerable loss of time takes place because of the time required to load and unload the body of the vehicle. One of the objects of the present invention is to provide means whereby while a vehicle is in use hauling a load from one point to another bricks may be placed in a stack within a separate body where they can await the arrival of the truck, whereupon said truck can be operated to lift the entire hack of bricks into position on the truck without any of the bricks becoming displaced relative to each other. The empty body left at the kiln or

yard can thus be filled and left awaiting the return of the truck. Thus the entire time of the truck is utilized in hauling and no tedious delays are necessary in order to permit loading or unloading of the truck.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

50 In the accompanying drawings the preferred form of the invention has been shown.

In said drawings:—

Figure 1 is a side elevation of a portion 75 of a truck having the present improvements combined therewith and showing the body in position when about to be loaded onto the truck.

Fig. 2 is a similar view showing the body 80 in position on the truck.

Fig. 3 is a rear elevation of the body and showing the bricks piled therein.

Fig. 4 is a front elevation of the body.

Referring to the figures by characters of reference 1 designates a portion of a truck of any preferred construction and upstanding from the rear portion of the chassis of the truck are brackets 2 to each of which is secured a frame 3 mounted to swing about a pivot 4 which constitutes a bearing for an anti-friction roller 5. This roller is located close to and inside of the frame 3. Secured to the frame is a rail 6 the rear portion of which is curved to form a hook 95 7 while the front portion is attached to a toothed segment 8 braced by an arm 9 extending from the frame 3. The segment is in mesh with a gear 10 secured to a shaft 11 which is adapted to be rotated by means of a crank arm 12 or in any other suitable manner. Each of the frames is provided with a toothed segment 8 and both segments mesh with gears 10, the shaft 11 being extended through both gears. This shaft is 100 journaled on any suitable supporting structure carried by the truck.

Each frame has an arm 13 extending downwardly and rearwardly from the pivotal portion thereof and on which is 110

journaled an anti-friction roller 14, this roller being mounted on a transverse shaft 15 to which is pivotally connected a hook 16.

The detachable body of the truck includes 5 parallel beams 17 on which are secured cross bars 18 having standards 19 at the ends thereof to which are secured the side panels 19' of the body. The bottom 20 of the body is secured on the transverse bars 18. A 10 heavy channel beam 20' is secured to the sides and bottom of the body at one end. The other end of the body is closed by a panel 21. Thus it will be seen that the body is closed at its bottom, sides and one end 15 while its top and one end are open.

An intermediate beam 22 is secured along the bottom 20 and is provided at one end with a supporting arm 23 which intersects the open end of the body and is perpendicular to the bottom 20.

20 Bearings 24 are secured to the ends 21 of the body and journaled therein is a shaft 25 on the end portions of which are journaled sleeves 26 having radial arms 27 which extend close to and lap the respective side 25 panels 19'.

Secured to the side portions of the channel beam 20' are brackets 28 to each of which is pivotally connected a U-shaped lever 29 one 30 end of which is pivotally attached as at 30 to a clamping shoe 31 while the other end is pivotally connected as at 31' to a link 32. All of the links 32 at each side of the body are pivotally connected to transverse links 33 35 and the intermediate portions of these transverse links are connected by links 34 to an equalizing link 35. This equalizing link is connected by a link 36 to one end of the adjacent arm 27.

40 An anti-friction roller 37 is mounted on each of the arms 27 and is so positioned that when the body is placed on end with the shoes 31 engaging the ground, said roller will be in position to engage the hook ends 45 7 of the rails 6.

Studs 38 extend laterally from the side portions of the body and are so located as to be readily engaged by the hooks 16 when the body is on end.

50 In using the apparatus, the body is placed on end as shown in Figs. 1, 3 and 4, and the bricks to be transported are piled within the body so as to brace the arm 23 as shown particularly in Fig. 3, these bricks practically filling the body. After the body has been filled the truck is backed up to it and the frames 3 are swung upwardly so that the hooks 7 will be readily insertible under the anti-friction rollers 37. The frames 3 55 are then swung downwardly and forwardly by means of the gears 10, thereby bringing the hooks 7 in engagement with the rollers 37 as shown in Fig. 1. As the downward movement of the segments 8 continues the 60 rear ends of the rails 6 will push upwardly

on the rollers 37 and thus cause the links 27 to swing about their pivots 27' and to pull through the links 36 upon the equalizing links 35 which will result in all of the shoes 31 being moved inwardly against the bricks so that those bricks between the opposed sets of shoes will be tightly clamped together and against the sides of the interposed arm 23. This clamping action takes place during the first portion of the upward movement of the rear ends of the rails 6. As said rails continue to move upwardly at their rear ends during the downward movement of the segments 8, the body with the load therein is swung forwardly and downwardly 70 until the bottom of the body is brought to position on the anti-friction rollers 5, whereupon the rollers 37 will gravitate downwardly and forwardly along the inclined rails 6 as shown in Fig. 2, thereby bringing the load onto the truck. The load can thus be conveyed to the point of delivery and in the meantime another body can be loaded ready for the return of the truck. When the truck reaches the point of delivery the 75 operation before described is reversed and the body is lowered with its lower end lowermost until it reaches the ground, the bricks being held against dropping out of the body by the clamping action of the shoes 31 upon the lower courses of the bricks forming the 80 huck. As soon as the body is deposited on the ground with the load, the shoes will be relieved of the pull exerted through the links and, by placing the hooks 16 in engagement 85 with the lugs 38 and moving the truck forward, the body will be pulled away from the bricks and the arm 23 will be withdrawn from under the courses thereabove. Thus the bricks will be left standing and their 90 delivery will be effected without breakage and without the necessity of counting them, it being known in advance how many bricks constitute a load sufficient to completely fill the body.

100 It is to be understood that it is not necessary to place the hooks 16 in engagement with the studs 38 during the loading operation.

105 What is claimed is:—

110 1. The combination with a truck, of a detachable body having an open end and top, means connected to the body for engaging the bottom portion of a huck of bricks or the like within said body when the body is 115 placed with its lower end lowermost, and co-operating means upon the truck and body for successively shifting said clamping means to grip the contents of the body and lift said body onto the truck.

120 2. The combination with a truck, of a detachable body, open at one end and at the top, clamping means upon the sides of the body and adjacent the open end thereof, and co-operating means upon the truck for suc- 125

130

cessively shifting the clamping means to bind upon the contents of the body and to elevate the body onto the truck.

3. The combination with a body open at

5 one end and at its top and opposed load gripping members at the sides of the body, of a truck, a supporting structure on the truck and mounted to swing about a substantially horizontal axis, and means upon the body 10 and coöperating with the supporting structure for successively shifting the gripping members to gripping position and lifting the body onto the truck.

4. The combination with a body having an

15 open top and end, of opposed series of gripping elements at the sides of the body, links pivotally connected to the sides of the body, equalizers connecting said links to the respective series of gripping elements, a truck, 20 and coöperating means upon the truck and links for successively actuating the gripping elements to bind upon a load and to grip the body with the load onto the truck.

5. The combination with a body having an

25 open top and end and a fixed supporting element extending across the open end of the body from the bottom thereof, of opposed series of gripping elements connected to the sides of the body at said end, a truck, a supporting structure mounted to swing on the truck about a substantially horizontal axis, means movably connected to the body for engagement by said structure, and equalizing connections between said means and the respective series of gripping elements.

35 6. The combination with a truck and a supporting structure mounted to swing thereon about a substantially horizontal axis, said structure including rails having hooks at their terminals, and means for

40 swinging the structure, of a body having an open top and end, a load supporting arm extending from the bottom of the body and across the open end thereof, opposed series 45 of gripping elements connected to the sides of the body for binding portions of a load against said arm, means movably connected to the body for engagement by the hooked ends of the rails, and mechanism operated by said means when shifted relative to the body for simultaneously actuating the gripping elements to bind the load.

7. The combination with a truck and a structure mounted to swing thereon about

55 a substantially horizontal axis, said structure having rails provided with hooked terminals, of a body having an open top and end, a load supporting arm extending from the bottom of the body and across said end, 60 opposed series of gripping elements for binding a portion of the load upon the arm, anti-friction means movably connected to the body for engagement by the rails, equalizing connections between said means and the gripping elements, and means operated

by the tilting of the supporting structure for successively actuating said gripping means and elevating the body onto the structure.

8. The combination with a truck, rails 70 mounted to swing thereon about transverse axis, of a load holding body, means actuated by the elevation of said body for binding upon the load, and means for actuating the rails to elevate the body and direct said body onto the truck.

9. The combination with a truck having anti-friction devices thereon at one end, of a tiltable structure including rails having hooked terminals, means for actuating said structure to elevate said hooked terminals and bring the rails to downwardly and forwardly inclined positions, a load holding body, means thereon for engagement by the rails to elevate the body and move it forwardly by gravity onto the truck, means operated by the elevation of the body for binding on the load.

10. The combination with a truck and a 80 tiltable structure thereon including rails having hooked terminals, of a body having an open end and top, said body being detachable from the truck, opposed load gripping elements carried by the sides of the body near the open end thereof, means on

85 the body for engagement by the hooked terminals of the rails, mechanism operated by the shifting of said means relative to the body for actuating the gripping elements, means for tilting the structure on the truck 90 to engage said means on the body and elevate the body onto the truck, and means on the truck for engaging the body to withdraw said body from the load while the body is standing with its open end downward.

11. The combination with a truck having a tiltable structure thereon including rails, 100 of a body having an open end and top and adapted to stand with said open end downward, means on the sides of the body for gripping the load within the body, means operated by the tilting of the structure on the truck for successively actuating the gripping means and lifting the body onto the truck, and coöperating means upon the truck and body for sliding said body away from the load while the body is standing on end.

12. The combination with a truck, of a 110 detachable body open at one end and at the top, means carried by the truck for setting the body upon the ground with its open top to the rear and with its open end downward, means carried by the body for releasing said body from its contents when the body is set upon the ground, and means coöperating between the truck and the body for withdrawing the body from its contents through the motive power of the truck when the contents of the body is so released. 120 125 130

13. The combination with a truck, of a detachable body having an open side, means carried by the truck for raising said body and depositing it upon the ground, and means incorporated in the body and actuated by the weight of the contents thereof, for gripping the contents while the body is being raised, and for releasing the contents when the body is deposited upon the ground, and means for dragging said body away from its contents when so released.

14. In a loading and unloading device, a conveying vehicle, a load-carrying body having an open top and an open end, means for carrying the said body upon the vehicle

with its open top upward, and means for applying the body thereto and removing it therefrom, the said body being adapted when removed from the vehicle to be deposited upon its open end and clamps located near 20 the open end of the body adapted to hold the contents while the body is being lowered.

In testimony that I claim the foregoing as my own, I have hereto affixed my signature in the presence of two witnesses.

ROBERT A. FONTAINE.
